UNITED STATES PATENT OFFICE.

CARL ERIC EKLIND, OF CHICAGO, ILLINOIS, ASSIGNOR OF ONE-HALF TO EDWARD POSSON, OF CHICAGO, ILLINOIS.

DRAFT-RIGGING FOR RAILWAY-CARS.

1,148,580.

Specification of Letters Patent. Patented Aug. 3, 1915.

Application filed June 22, 1914. Serial No. 846,513.

To all whom it may concern:

Be it known that I, CARL ERIC EKLIND, a citizen of the United States, residing at Chicago, in the county of Cook and State of Illinois, have invented certain new and useful Improvements in Draft-Rigging for Railway-Cars; and I do hereby declare the following to be a full, clear, and exact description of the invention, such as will enable others skilled in the art to which it appertains to make and use the same.

My invention has for its object to provide an improved draft rigging for railway cars, and to such ends, the invention consists of the novel devices and combinations of devices hereinafter described and defined in the claims.

Particularly, my invention has for its object to provide a simple, strong, durable, and efficient connection between a draw bar and yoke, which dispenses with the use of rivets or bolts, and which makes it an easy and a simple matter, either to connect together, or to disconnect the draw bar and yoke. Briefly, I accomplish the above desired result by so constructing the draw bar and yoke that they can be interlocked by lateral movement of the one in respect to the other, and in connection therewith, provide a coupling sleeve, preferably formed as a part of the front follower, and which, when slid over the interlocking portions of the draw bar and yoke, securely holds the same against lateral displacement, and hence, operatively coupled together.

The invention is illustrated in the accompanying drawings wherein like characters indicate like parts throughout the several views.

Referring to the drawings: Figure 1 is a view partly in plan and partly in horizontal section, showing my invention incorporated in a draft rigging; Fig. 2 is a vertical section taken on the line $x^2 x^2$ on Fig. 1, but with some parts shown in full; Fig. 3 is a perspective view showing the yoke and the combined front follower and coupling sleeve, with the bridge piece removed in order that certain other parts may be more clearly shown; Fig. 4 is a perspective view of the draw bar, the coupler end thereof being broken away; Fig. 5 is a perspective view showing the interlocking portions of the draw bar and yoke, portions of both being broken away; Fig. 6 is

a perspective view showing the draw bar, yoke and coupling sleeve, portions of the draw bar being broken away; and Fig. 7 is a transverse section taken on the line $x^7 x^7$ on Figs. 1 and 2.

The numeral 1 indicates the floor structure, the numeral 2 one of the end sills, the numeral 3 the draft sills, 3^a the center sills, and the numeral 4 a buffer bracket or casting which is secured to the end sill 2 and is provided with an opening through which the coupler draw bar works in the usual way.

It may be here stated that in the drawings I have illustrated a draft rigging having springs arranged in tandem, although the rigging so far as the arrangement of the springs is concerned, may take various forms. Describing, however, the construction shown for illustrative purposes, it may be stated that the outer, inner and intermediate draft lugs 5, 6 and 7, are afforded by metallic plates properly bent to form the said lugs and rigidly secured to the draft sills by rivets.

The coupler draw bar 8 is provided at its outer end with a coupler head 9 and at its inner end is vertically increased in dimensions at 10 to afford a shoulder head with which the draw bar yoke is adapted to be interlocked. The said shoulder head or inner end of the draw bar is shown as provided with vertical bolt holes, but this is immaterial, so far as the present invention is concerned. In fact, the complete draw bar and coupler illustrated are of the standard Master Car Builder's type. The vertical bolt holes are simply superfluous.

The draw bar yoke 12 may, of course, take various forms and may be either a cast or forged structure. As shown, it is provided with an intermediate follower engaging bar 13 formed integral therewith, and at its front ends, it is increased in strength and thickness and formed with inner and outer longitudinally spaced lugs 14 and 15 that engage, respectively, with the inner and outer shoulders 16 and 17 of the shouldered inner end of the draw bar 8. Here it is important to note that the said shoulders 14 and 15, in a horizontal direction, are curved (see particularly Figs. 3 and 5), so that the shouldered inner end of the said draw bar is loosely held between the same with freedom for horizontal oscil-

latory movements of the draw bar. The well known purpose of lateral oscillatory motion of the coupler draw bar is to relieve the draft rigging from undue strains in traveling curves. The said curved surfaces might, of course, be either on the yoke, as described, or on the shouldered head of the draw bar, as in either instance they would permit the lateral swinging movement without bending on square or flat bearings.

The above described draw bar and yoke, may, as is evident, be assembled and interlocked by lateral motion, and also separated by lateral motion. When held in axial alignment, they are operatively interlocked; and to hold them thus operatively aligned and interlocked, I provide a coupling sleeve 18 which is preferably cast integral with the front follower 19. This coupling sleeve 18, in vertical cross section, is rectangular, and in horizontal section, is made flaring, so as not to interfere with the lateral oscillation of the draw bar. The front follower 19, which affords a back or inner wall to the coupling sleeve, is provided with upper and lower rectangular perforations through which the shouldered ends of the yoke 12 are adapted to freely pass, leaving between the said openings, a transverse portion 20, the front face of which is rounded in a horizontal direction, as best shown in Fig. 1. This rounded face of the parts 20 of the front follower, normally engages with the inner end of the draw bar and permits free lateral oscillation of said draw bar.

In the illustrated arrangement, the rear follower 21 and two intermediate followers 22 are extended through the yoke 12 and engage with the rear draft lug 6 to the intermediate draft lug 7, as clearly shown in Fig. 1. The said follower 21 is also engageable with the rear end portion of the yoke 12, and the two intermediate followers 22 are engageable with the intermediate bar 13 of said yoke. Coiled springs 23 are interposed between the front follower 19 and the front member of the intermediate followers 22, and between the rear member of the intermediate followers 22 and the rear follower 21.

It will be understood that, so far as this invention is concerned, it is immaterial whether or not a frictional device is incorporated in the draft gear, and also whether the springs are arranged in tandem, or otherwise. All of the followers, in the construction illustrated, are arranged to slide upon guide bars 24, which, as shown, are bolted to the draft lugs 5, 6 and 7.

Under bumping strains, the rear end of the draw bar will be forced against the curved front face of the front follower 19 and against the lugs 14 of the yoke, thereby causing the springs 23 to be simultaneously compressed. Under draft strains, the draw

bar shoulder 17, acting on the front lugs 15 of the yoke, will draw the yoke forward with it, thereby simultaneously compressing the springs 23. Under bumping strains, the draw bar yoke and combined front follower and coupling sleeve move together, but under draft strains, the draw bar and yoke move together while the combined front follower and coupling sleeve remain stationary, being held against forward movements by the front draft lugs 5. The interlocking portions of the draw bar and yoke, however, even under draft strains, can never be drawn out of the coupling sleeve, and hence, the coupling sleeve is always in position to prevent lateral separation of the draw bar from the yoke. The construction described is extremely simple, of small cost, strong, durable, eliminates the use of bolts and rivets, as a means for coupling together the draw bar and yoke, and provides an arrangement in which the draw bar and yoke may be very easily coupled together or separated.

What I claim is:

1. In a draft rigging, the combination with draft lugs, front and rear followers and coöperating springs, of a yoke coöperating with said springs and followers, the said front followers having openings through which the front ends of said yoke are passed, a draw bar having at its rear end a shouldered head operative on said front follower and having interlocking engagement with the front ends of said yoke, by lateral movement, and a coupling sleeve applied to said front follower and normally holding said draw bar yoke against separation, and hence, operatively connected.

2. In a draft rigging, the combination with a draw bar having interlocking engagement adapting it to be interlocked and disconnected by lateral movement, certain of the interlocking surfaces of said members being curved to permit lateral oscillation of said draw bar, a coupling sleeve slideable thereon, to and from position to hold said draw bar and yoke against lateral separation, and hence, operatively interlocked, and a front follower to which said coupling sleeve is applied, said follower having a curved surface with which the end of said draw bar is engageable.

3. In a draft rigging, the combination with draft lugs, followers and coöperating springs, of a draw bar having a shouldered head, a yoke having front and rear lugs embracing the shouldered head of said draw bar and arranged to be connected and disconnected from said draw bar by lateral movement, and a coupling sleeve on the front follower telescoped over the interlocking portions of said draw bar and yoke and holding the same against lateral displacement, and hence, operatively inter-

locked, the side walls of said coupling sleeve having a forward flare permitting lateral oscillation of said draw bar, the front and rear lugs on said yoke and the front face of the front follower having horizontally rounded surfaces for facilitating the lateral oscillation of said draw bar.

In testimony whereof I affix my signature in presence of two witnesses.

CARL ERIC EKLIND.
